UNITED STATES PATENT OFFICE

MICHAEL W. MCARDLE, OF CHICAGO, AND GEORGE BROWNING, OF WILMETTE, ILLINOIS,
ASSIGNORS TO CHICAGO FLEXIBLE SHAFT COMPANY, OF CHICAGO, ILLINOIS, A
CORPORATION OF ILLINOIS

ATTACHMENT PLUG FOR ELECTRIC HEATING DEVICES

Original application filed February 10, 1927, Serial No. 167,108. Divided and this application filed June 30, 1930. Serial No. 464,732.

This application is a division of our pending application, Serial No. 167,108, filed February 10, 1927.

The purpose of the present invention is to provide an improved construction of an attachment plug of the type designed for use with portable electrical devices, such as heaters, toaster stoves, flat irons and the like, having in combination with the attachment plug a control switch including a snap action arranged for ready removal and replacement if occasion should require, the specific purpose of the invention being to render such construction simple and economical both in the manufacture of the parts and in the assembly of them. The invention consists in the elements and features of construction shown and described as indicated in the claims.

20 In the drawings:

Figure 1 is a top plan view of a plug embodying this invention disconnected from the electrical device which it serves.

Figure 2 is a partly sectional side elevation of the same.

Figure 3 is a section at the line 3-3 on Figure 1.

Figure 4 is a section at the line 4-4 on Figure 2.

30 Figure 5 is a section at the line 5-5 on Figure 4.

Figure 6 is a detail section at the line 6-6 on Figure 5.

35 Referring to the drawings in detail:

The contact elements are housed in a metallic shell, 1, from which the cable, 2, containing lead wires, 3 and 4, emerges at one side and extends in a coiled metallic sheath, 6, which is bent at right angles, as indicated, 40 so that when the plug is mounted on an electric flatiron, the cable, 2, will trend rearwardly and upwardly in a plane which is laterally offset from that of the handle of the iron, out of the way of the operator.

45 At the lower end the shell is formed with apertures, 12, 12, through which are admitted the contact prongs (not shown) of the electric appliance with which the plug is used, suitable provision being made for insulating the prongs from the shell at the edges of the aper-

tures through which the prongs protrude into the shell for engaging the contact members within the latter. Each of these contacts consists of two metal parts, 15 and 16, formed and arranged, as may be readily understood from the drawings without detail description, for being stressed toward each other to grip between them and obtain sure contact with the inserted prongs.

55 One of the contact members, 16, carries a binding screw, 26, to which the lead wire, 3, is directly attached. The other lead wire, 4, is connected by a binding screw, 27, to a lug, 28, of the fitting, 28, anchored on an insulating sheet, 18, and having an up-standing contact lug, 29, for engaging with a swinging switch arm, 30, which is electrically connected with the other contact member, 16. Said arm, 30, is pivoted at 31 to a support, 38, extending from the under side of the part, 16, as seen in Figure 3, said support being clamped in position by the securing of the part, 16, to said insulating sheet, 18.

60 The switch arm, 30, has spaced up-turned lugs, 33, at its movable end, one of said lugs serving for contact with the part, 29, and the space between said lugs accommodating an actuator in the form of a U-shaped lever, 34, which is a part of a "snap action" assembly carried in a cap block, 35. This block is of 65 insulating material, being molded in a form to serve for a convenient finger grip in applying or withdrawing the plug from the electrical device which it serves; and the block, 35, is secured to the upper end of the shell, 31, in a manner to permit of its easy removal therefrom, which may be understood from the drawings and requiring no specific description for the purpose of the present invention.

70 Within the cap block, 35, the snap action for operating the switch arm, 30, is secured by transverse screws, 42, whose heads are slightly sunken to avoid danger of short-circuiting, and which extend through a U-shaped mounting frame, 43, accommodated in a suitable recess in the cap block, 35, and entered therein from the under or inner side. A rocking lever, 44, is pivoted at 45 in said frame, 43, said lever having its two arms, 75 100

46, 46, engaged respectively with push buttons, 47 and 48, which are slidably carried in suitable ports in the block, 35. The frame, 43, has out-turned lugs, 49, which serve as 5 pivots for a swinging actuator member, 34 which engages the switch arm, 30; and reacting between the lower end of said actuator, 34, and a yoke at the end of the short middle arm, 50, of the lever, 44, a spring, 51, 10 on a guide stem, 52, stresses the parts to hold them at one limit or the other of their range of movement, and acts to carry them past the middle position when one or the other of the buttons, 47 or 48, is depressed. The 15 actuator, 34, being merely inserted between the lugs, 33, of the lever, 34, it is readily withdrawn when the cap block, 45, is removed; and if the snap action should require repair, it can be removed from the block upon with- 20 drawing the screws, 42, which hold the frame, 43, in place.

We claim:

1. In an attachment plug, a shell apertured at one end to receive contact prongs, 25 yielding contact devices housed in the shell, a contact member; a movable switch arm associated with one of said devices, circuit wires entering the shell and attached respectively to the other contact device and to 30 said contact member, said contact member being arranged to co-operate with said switch arm, and a cap member removably secured to the opposite end of the shell, a snap action device and actuating means therefor mounted 35 in said cap, said snap action device comprising a part extending into engagement with the switch arm.

2. In an attachment plug, a shell apertured at one end to receive contact prongs, 40 yielding contact devices housed in the shell, a movable switch member mounted in the shell, and a removable cap block serving as a closure for the other end of the shell, with switch-actuating means carried by said block 45 having a part extending for engagement with the movable switch member in the shell, said shell having laterally projecting flanges at the end which receives the cap block, and the block having grooves in its sides adja- 50 cent said flanges and a channeled locking member laterally slidable over the flanges of the shell and simultaneously engageable with the grooves of the block for locking the latter in place.

55 3. In the combination defined in claim 1, said cap member having downwardly tapering lateral surfaces adapting it to serve as a finger grip for withdrawing the shell endwise from the contact prongs.

60 4. In the combination defined in claim 1, said cap member having downwardly tapering lateral surfaces adapting it to serve as a finger grip for withdrawing the shell endwise from the contact prongs, and the actuating means of the snap action in said cap

member comprising a member which projects through the top surface of the cap.

5. In the combination defined in claim 2, said channeled member being approximately U-shaped with its parallel arms channeled 70 for the said locking engagement, and with a lug on its connecting portion projecting parallel to the side of the shell for inserting or withdrawing the U-shaped part.

6. An attachment plug comprising a shell 75 apertured at one end to admit contact prongs, and a removable cap block serving as a closure for the other end of the shell; contact devices for co-operating with contact prongs; switch means controlling circuit connection 80 between the contact devices comprising a snap action switch mounted in said shell and cap block, and exteriorly operable switch-operating means carried by the cap member, said cap member having downwardly tapering 85 lateral surfaces adapting it to serve as a finger grip for withdrawing the shell endwise from the contact prongs.

7. An attachment plug comprising a shell apertured at one end to admit contact prongs, 90 and a removable cap block serving as a closure for the other end of the shell; contact devices for cooperating with contact prongs; switch means controlling circuit connection 95 between the contact devices comprising a snap action switch mounted in said shell and cap block, and exteriorly operable switch-operating means carried by the cap member, said cap member having downwardly tapering lateral surfaces adapting it to serve as a finger grip for withdrawing the shell endwise from the contact prongs, and the actuating 100 means of the snap action in said cap member comprising a member which projects through the top surface of the cap.

In testimony whereof, we have hereunto set our hands at Chicago, Illinois, this 26th day of June, 1930.

MICHAEL W. McARDLE.

GEORGE BROWNING.
